FIG. 6 is a right side view of FIG. 2;
FIG. 7 is a perspective view of the first upright cabinet module of the modular storage unit set of FIG. 1;
FIG. 8 is a top view of FIG. 7;
FIG. 9 is a left side view of FIG. 7;
FIG. 10 is a front view of FIG. 7;
FIG. 11 is a right side view of FIG. 7;
FIG. 12 is a perspective view of the second upright cabinet module of the modular storage unit set of FIG. 1;
FIG. 13 is a top view of FIG. 12;
FIG. 14 is a left side view of FIG. 12;
FIG. 15 is a front view of FIG. 12;
FIG. 16 is a right side view of FIG. 12;
FIG. 17 is a perspective view of the upright drawer module of the modular storage unit set of FIG. 1;
FIG. 18 is a top view of FIG. 17;
FIG. 19 is a left side view of FIG. 17;
FIG. 20 is a front view of FIG. 17;
FIG. 21 is a right side view of FIG. 17;
FIG. 22 is a perspective view of the first full upright cabinet module of the modular storage unit set of FIG. 1;
FIG. 23 is a top view of FIG. 22;
FIG. 24 is a left side view of FIG. 22;
FIG. 25 is a front view of FIG. 22;
FIG. 26 is a right side view of FIG. 22;
FIG. 27 is a perspective view of the second full upright cabinet module of the modular storage unit set of FIG. 1;
FIG. 28 is a top view of FIG. 27;
FIG. 29 is a left side view of FIG. 27;
FIG. 30 is a front view of FIG. 27;
FIG. 31 is a right side view of FIG. 27;
